UNITED STATES PATENT OFFICE

STANLEY ANTHONY, OF BOSTON, MASSACHUSETTS

CABINET INDEX

Application filed February 7, 1930. Serial No. 426,572.

This invention relates to cabinet indexes and pertains more particularly to improvements in indexes of the type in which index material is mounted upon movable carriers or supporting members which are normally housed in upright position within a cabinet and which are mounted to swing in vertical planes into and out of the cabinet.

In my copending application for card index, Serial No. 223,391, filed October 1, 1927, I have described and claimed an index device of the aforesaid type in which the card panels are mounted upon elongate supporting members pivoted at their upper ends to 15 lever arms which are pivoted in turn to upright supports arranged at the rear of the cabinet, the pivots connecting the arms to their respective supports being remote from the upper ends of said supports so that the 20 arms move angularly with respect to the supporting members when said members are swung outwardly and downwardly of the cabinet. In this arrangement it is necessary to provide means for limiting the downward 25 swing of the lever arms in order to stop the outward movement of the panel holders, and in my said application I provide a stop member and brace pivoted to each of the upright supports and linked to the corresponding 30 lever arm to limit the movement of the arm.

While this construction is generally satisfactory, I have found that the necessity of a separate stop member may be obviated and that the construction and operation of the 35 index is improved by so arranging the connecting means that a single member or arm will serve to connect the panel-supporting members to the upright supports for swinging movement outwardly of the cabinet, and 40 to limit such outward movement. It is accordingly the principal object of the present invention to provide an elongate arm pivoted to the upright support and slidably connected to the panel-supporting member or 45 carrier so that the carrier may move a limited distance longitudinally of the arm and is restrained from angular movement with respect to the arm. Another object is to provide a latch also pivoted to the support and 50 arranged to engage the arm when the sup-

porting member is extended, thereby to prevent upward movement of said arm and member.

A recommended embodiment of the invention is illustrated in the accompanying drawings, in which:

Fig. 1 is a perspective view of a cabinet index equipped with the improved connecting means, one of the carriers being swung outwardly to display the index cards carried by 60 a pair of panels pivotally mounted on the carrier;

Fig. 2 is a vertical section through the index cabinet showing the extended carrier and its connecting members in elevation; 65

Fig. 3 is an enlarged elevation of the carrier and connecting arm in closed position within the cabinet;

Fig. 4 is an enlarged detail of a portion of the connecting members illustrated in 70 Fig. 2;

Fig. 5 is a similar view showing an intermediate position of the connecting members; and

Fig. 6 is a section on line 6—6 of Fig. 4. 75

As more fully described in my said application, the index preferably comprises a cabinet 1 having vertical compartments open at the front and separated by parallel upright partitions 2 and having a hinged shelf 80 3 normally supported in front of the cabinet and provided with foldable wings 4, the upper surface of the shelf constituting a forward extension of the cabinet bottom 5, the bottom 5 and shelf 3 having aligned tracks 85 6 and 7 respectively; a panel-supporting member or carrier 8 normally housed in upright position within each compartment and mounted to swing in a vertical plane into and out of the cabinet over the tracks 6, 7; a pair 90 of card-supporting panels 9 pivoted to each carrier 8, the panels having top and bottom pintles 10 and 11 removably journaled in upper and lower flanges 12 and 13 respectively of the carrier, whereby the panels may be 95 folded together within the compartment or opened out (Fig. 1) to display the cards 14 mounted thereon in overlapping relation; and connecting means for supporting and guiding the upper end of the carrier 8 dur- 100

ing its movement outwardly and downwardly of the compartment. The shelf 3 is arranged to swing upwardly over the open front of the cabinet and, in case the shelf is 5 shorter than the height of the cabinet, a hinged cover 15 may be provided to fold over the upper portion of the cabinet front, thereby to close the cabinet when the index is not in use.

10 The connecting elements which constitute the subject matter of the present invention preferably comprise a rigid upright support 16 having flanged ends fastened as by screws 17 to the top and bottom of the cabinet at 15 the rear of each compartment, and an elongate arm 18 pivoted at 19 to the upright 17 within the upper portion of the cabinet and slidably connected to the carrier 8 so that the carrier may slide longitudinally over the 20 outer edge of the arm. The under side of the carrier preferably has one or more pairs of opposed brackets or guides 20 arranged to straddle the link 18 and the complementary guides carry a transverse pin or bolt 21 which 25 passes through an elongate slot 22 formed in the link. Hence the carrier 8 is held flatwise upon the outer edge of the arm 18 and is 30 slideable longitudinally of said arm, the extent of such sliding movement being limited by the length of the slot 22.

The carrier 8 may be substantially as long as the height of the compartment and its lower end is preferably provided with a grooved roller 23 traveling on the raised 35 tracks 6 and 7 and supporting the bottom of said carrier and its card panels. The side flanges of the grooved roller guide the roller along the track and effectively prevent transverse displacement of the lower end of the 40 carrier during outward or inward movement of the rollers. Such movement is usually effected by grasping the outer edges of the folded panels near the bottom thereof and swinging the panels and their supporting 45 and connecting members outwardly or inwardly of the cabinet as desired. When in its outermost position (Figs. 1, 2 and 4), the panel-supporting member 8 is held at the proper inclination over the shelf 3 by the 50 arm 18 which supports its upper end, for it will be noted that the connection between these parts constrains the carrier to move parallel to the arm, thereby preventing relative angular movement thereof, and that the 55 downwardly sliding movement of the member 8 on link 18 is limited by the abutment of the lowermost pin 21 at the end of the link slot 22.

In order to prevent the connected members 60 8 and 18 from swinging upwardly on the pivot 19 when the panel-supporting member is fully extended (Fig. 2) I preferably provide a latch 24 pivoted at 25 to the upright 16 at a point below the pivot 19 and provided with a transverse hook or stud 26 near

its outer end arranged to engage over the outer edge of the arm 18. Said arm preferably has a notch 27 (Figs. 4 and 5) receiving the hook 26 in said extended position, so that the arm and carrier are held at a fixed 70 inclination to the cabinet front. The pivoted latch swings substantially in the plane of the arm 18 and upright 16 so that, when the carrier 8 is pushed upwardly to carry the panels into the cabinet compartment, the 75 lower edge of the latch is engaged by the flange 12 (Fig. 5) and the latch is carried upwardly to its closed position (Fig. 3) alongside the upright 16. Said upright may have an edge recess 28 receiving the hook 26 in 80 said closed position. As the carrier 8 is again withdrawn from the cabinet, the latch swings downwardly by action of gravity with its lower edge sliding on the flange 12 until the hook 26 engages the outer edge of 85 arm 18 and finally locks within notch 27.

The operation of the index is apparent from the foregoing description, and it will be observed that the carrier 8, the upright support 16, connecting arm 18 and latch 24 90 may be assembled as a unit and mounted in the cabinet with the upright arranged at proper position according to the depth of the cabinet. The improved connecting elements 95 may be economically manufactured, and, as said members are normally concealed within the cabinet even when the panels are extended, they may be made of inexpensive materials. The dimensions of the parts may be such as to conform to a cabinet of any desired 100 size, and it is apparent that the movable parts swing readily without binding. It will be understood that structural details of the cabinet index herein described may be varied 105 to suit particular purposes without departing from the essence of my invention, as defined in the appended claims.

From the foregoing it is evident that the principal feature of this invention is the provision of an improved cabinet index comprising a carrier or panel-supporting member normally housed in upright position within the cabinet with its lower end supported by the cabinet bottom, an arm pivoted within 110 the upper portion of the cabinet and so connected to the carrier that the carrier is slideable along the arm parallel thereto when its lower end is moved outwardly of the cabinet onto a suitable support, and means, preferably associated with the connection between 115 the arm and slideable carrier, for limiting the outward movement of the carrier, so that the carrier is supported at an inclination to the cabinet front in its extended position, as indicated in Fig. 2. The latch for restraining 120 swinging movement of the extended arm and carrier and the track and cooperating roller for guiding the lower end of the carrier are desirable features of the improved complete 125 index; but the precise character, construction 130

or engagement of the index panels and cards, or other holders for index material, are not essential to this invention.

I claim:

- ed to the arm and normally housed in upright position within the cabinet alongside the support, the arm having a longitudinal slot therethrough and the under side of the carrier having a transverse connecting member extending through the slot and movable longitudinally thereof so that the carrier is constrained to slide along the arm in a direction parallel to the arm, when the lower 5 end of the carrier is moved inwardly or outwardly of the cabinet, and means for supporting said lower end when the carrier is moved to extended position in front of the cabinet, said transverse connecting member 10 abutting the end of the slot when the carrier is extended, thereby to limit the outward movement of the carrier and support the carrier at an inclination to the cabinet front. 15 9. An index comprising a cabinet open at the front, an upright support fastened at top and bottom adjacent the rear of the cabinet, an arm pivoted to said support at the upper portion of the cabinet for swinging movement toward its front, a carrier slidably connected to the arm and normally housed in upright position within the cabinet alongside the support, the arm having a longitudinal slot therethrough and the under side of the carrier having a transverse connecting member 20 25 30 35 40 45 50 55 60 65 70 75 80 85 90 95 100 105 110 115 120 125 130 member extending through the slot and movable longitudinally thereof so that the carrier is constrained to slide over the outer surface of the arm in a direction parallel to the arm when the lower end of the carrier is moved inwardly of the cabinet, and means for supporting said lower end when the carrier is moved to extended position in front of the cabinet, said transverse connecting member abutting the outer end of the slot when the carrier is fully extended, thereby to limit the outward movement of the carrier and support the carrier at an inclination to the cabinet front, and a latch pivoted to the upright support below the arm pivot and swinging in a plane parallel to that of the arm, the arm having a notch in its outer edge and the latch having a transverse hook adjacent its free end engaging in said notch when the carrier is fully extended, thereby to prevent upward swinging movement of the arm and carrier. 10. An index comprising a cabinet open at the front, and having a shelf supported at its open front and constituting an extension of the cabinet bottom, a carrier normally housed in upright position within the cabinet, the cabinet bottom and shelf having aligned tracks leading outwardly of the cabinet 115 120 125 130 net and the lower end of the carrier having a grooved roller traveling on said tracks thereby to guide and support the bottom of the carrier when it is moved toward and from the cabinet and to restrain transverse displacement of the carrier, an arm pivoted

within the upper portion of the cabinet, and means connecting the arm to the carrier so that the carrier slides along the arm as its lower end is moved inwardly or outwardly on said tracks, and complementary means for limiting the outward movement of the carrier, thereby to support the extended carrier at an inclination to the cabinet front.

Signed by me at Boston, Massachusetts, this fifth day of February, 1930.

STANLEY ANTHONY.
